US00D617459S

(12) **United States Design Patent**
Bogue

(10) **Patent No.:** **US D617,459 S**
(45) **Date of Patent:** **** Jun. 8, 2010**

(54) **PROSTHETIC VALVE**

(76) Inventor: **David Robert Bogue**, P.O. Box 301,
Layton, NJ (US) 07851

(**) Term: **14 Years**

(21) Appl. No.: **29/325,611**

(22) Filed: **Oct. 3, 2008**

(51) LOC (9) Cl. **24-03**

(52) U.S. Cl. **D24/155; D12/197**

(58) **Field of Classification Search** **D24/155, D24/156, 180, 176; 433/173, 176, 125, 126; 606/304, 74, 72; 623/25, 33, 34; D23/250; D8/312; D12/197**
